ATTORNEYS

UNITED STATES PATENT OFFICE.

WALTER GEORGE WILKES, OF BILOXI, MISSISSIPPI.

CASTING BOX.

Application filed October 21, 1922. Serial No. 598,138.

To all whom it may concern:

Be it known that I, WALTER G. WILKES, a citizen of the United States of America, and a resident of Biloxi, in the county of 5 Harrison and State of Mississippi, have invented a new and Improved Casting Box, of which the following is a description.

My invention relates to stereotyping machines and more particularly to the casting 10 box thereof for making high type cuts or plates or the like.

The general object of my invention is to provide an improved casting box and a 15 novel form of coating gage or stop-off bar whereby to make it possible to produce a type-high cored cast of any size with crossing "legs" or ribs so that any size cut produced will stand upright and also having bearing surfaces on all sides.

20 In carrying out my invention I produce the back platen of the mold not only with vertical grooves as is usual but with horizontal crossing grooves and I provide the movable gage or stop-off bar with tongues 25 or teeth that exactly fill the horizontal grooves closing the same against the escape of the metal.

Reference is to be had to the accompanying 30 drawings forming a part of this specification, it being understood that the drawings are merely illustrative of one example of the invention.

Figure 1 is a perspective view of a stereotyping outfit having a casting box and gage 35 bar formed in accordance with my invention, the view showing the mold in open position, that is to say, with the front platen brought away from the back platen into horizontal position;

40 Figure 2 is a side elevation with a portion broken away, the mold being shown closed;

Figure 3 is a side elevation of my improved gage or stop-off bar;

45 Figure 4 is a horizontal section as indicated by the line 4—4, Figure 2;

Figure 5 is a face view of the front platen and a modified arrangement of gages;

50 Figure 6 is a fragmentary face view of the back platen in modified form;

Figure 7 is a cross section on the line 7—7, Figure 6.

The illustration of my invention shows the same incorporated in a known stereotyping outfit. The numeral 10 indicates the frame; 11, the back platen; and 12, the

front platen. Said back platen has vertical grooves 13 as is customary and in addition said platen, in accordance with my invention, is formed with crossing horizontal 60 grooves 14.

The numeral 15 indicates an L-shaped gage or bar at two sides of the front platen while the numeral 16 indicates the second gage or stop-off bar, each gage bar 15, 16 65 having a handle 17. Any approved link assemblage 19 is provided to cause parallel movement of bar 16 when shifted by grasping its handle 17. It will be observed that the gage bars 15, 16 are formed with tongues 70 or teeth 18 spaced to correspond with the grooves 14 and to enter said grooves when the front platen 12 is closed against the back platen.

The crossing grooves 13, 14 serve to produce crossing legs or ribs on the cast being made so that any size cut will stand upright and present bearing surfaces on all sides.

The numeral 20 indicates a known arrangement of links connecting the front 80 platen 12 with the frame 10 to permit of a movement of said platen 12 from the closed vertical position to an open horizontal position.

To make a cast with the described mold 85 the paper matrix is laid on the flat side of the mold face up the gage bar or metal retainer 15 is placed over the adjacent edge of the matrix and the bar 16 is placed any desired distance from the bar 15 so that with 90 the closing of the front mold against the back mold the tongues 18 by entering the grooves 14 will close said grooves and prevent escape of the metal at either side. The tongues 18 are made type high from the 95 edges of the tongues to the bases or the flat sides of the bars 15, 16 presented to the matrix. The tongues 18 and the grooves 13, 14 are V-shape.

In Figure 5 the bar 115 corresponding 100 with the bar 15 is L-shaped in plan and it contacts with a plain flat edge portion 21 on the back platen. In Figure 6 there is a gate passage 22 extending partially along one side of the flat edge portion 21 and 105 adapted to receive material from the spout 23 at a side of the casting box 24. It will be understood that the spout in practice may be disposed on the casting box in other positions. In the back platen, Figure 1, similarly, is shown a vertical side gate passage 110 122 for the material received from the cast-

ing box, the spout 23 being similarly positioned.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A casting box including platens, a pair of gage bars on one platen, means permit-

ting adjustment of one of said bars relative to the other, said platens constructed to maintain the bars in parallelism.

2. A casting box including platens, one of which is formed with longitudinal and transverse grooves, a pair of gage bars on the other platen, said gage bars each having tongues to enter the transverse grooves, and equalizing links connected to one bar to maintain it in parallelism with the other bar regardless of its adjustment relative to said bar.

WALTER GEORGE WILKES.
